UNITED STATES PATENT OFFICE.

NOAH S. AMSTUTZ, OF CLEVELAND, OHIO.

ILLUSTRATIVE TELEGRAPHY.

1,019,403.

Specification of Letters Patent. Patented Mar. 5, 1912.

Application filed August 30, 1901. Serial No. 73,813.

To all whom it may concern:

Be it known that I, NOAH S. AMSTUTZ, a citizen of the United States, residing at Cleveland, in the county of Cuyahoga and 5 State of Ohio, have invented certain new and useful Improvements in Illustrative Telegraphy, of which the following is a specification, reference being had therein to the accompanying drawing.

10 This invention relates to the art of reproducing sketches, photographs, etc., locally or at a distance and is especially adapted to those methods which depend upon the synchronic movement of the transmitting and recording instruments.

15 The object of the invention is to provide a simple method for synchronizing the apparatus at both stations with great frequency whereby the most perfect synchronization is obtained.

20 In practicing this invention the electric impulses which affect the recording magnet perform in addition to this, the work of synchronizing the transmitting and recording instruments; hence the instruments are synchronized with every printing- or "image-impulse." The accuracy and desirability of such an effect is manifest.

25 The invention consists in the operations whereby these results are attained, all of which will be more fully described herein-after and particularly set forth in the claims.

30 The drawing illustrates diagrammatically an adaptation of apparatus to the purpose of this invention.

35 Figure 1 represents the transmitting apparatus. Fig. 2 represents the receiving or recording apparatus. Fig. 3 represents a 40 horizontal section of part of the transmitting apparatus and taken on the line 3—3 of Fig. 1. Fig. 4 represents a developed view of a contact plate.

45 Referring to the parts by letter, A, represents a rotatable drum which may be of a transparent material, such as glass. Upon the shaft thereof is rigidly secured a belt pulley a' ; and this belt pulley drives a pulley C, which in turn drives by means of 50 bevel-gears c , d , a vertical spindle E. This spindle has a reduced extension e upon which is feathered a sleeve E'. A radial arm e' is rigidly secured to the said sleeve E', and carries a small weight e^2 and the 55 tip e^3 thereof is adapted to rotate in contact

with the inner wall of a cylindrical box F. The contact strip G may be wrapped on the inner wall of this box F and may be embedded in said wall, as shown, in Fig. 1; its lower edge g may lie near the bottom of 60 said box and its extreme tip g' may fall a little short of contact with the vertical edge g^2 , as shown; it is provided with a terminal or binding post g^3 . The contact strip G may be insulated from the box F in any 65 suitable manner, or the box itself may be formed of insulating material, as shown. The sleeve E' is supported as shown, upon a loose collar H and a link h connects this collar with a pivoted lever h' , to the opposite arm of which is secured the core h^2 of the solenoid K and a small spring h^3 normally supports the weight of this sleeve. Collars e^4 , e^5 limit the movement of the 70 sleeve E'.
75

Upon the surface of the drum A, to which reference has already been made, may be wrapped a transparent representation B of the subject, which consists of celluloid or other transparent material, and adjacent to 80 this transparency B may be mounted a selenium cell N. An electric circuit n connects the base of this selenium cell with the coil n' of the solenoid K and a battery n^2 supplies current for the same.
85

It will be remembered that selenium has the remarkable quality of being affected by the amount of light shed upon it, in such a manner as to give a varying resistance to the passage of electric currents through it. Now as the drum rotates, the selenium cell N is moved longitudinally thereof and a small pin hole n^3 of the selenium cell will pass successively over all parts of the surface; in this manner the current in the circuit n is made to vary with the variations of light and shade of the subject and the core h^2 affects the sleeve E' so as to raise or lower the same proportionally with the light and shade of the subject.
90
95
100

At the receiving station is provided a rotatable drum R which may be driven continuously through the shaft r by means of a slip connection r' ; which slip connection may consist substantially of two disks r^2 one of which is pressed against the other by means of a spring r^3 . Bevel-gears r^4 transmit the rotation of this shaft to the drum R.
105

The gear-train O is driven by the shaft r^5 110

of the drum R and eventually drives the pinion o; this pinion drives an armature or needle o' rotatably mounted between the circumferentially disposed poles P; an electro-magnet M is provided adjacent to the drum R, an armature m, coöperating therewith to control the movement of the recording point m'; adjustable stops m² limit the movement of the recording point and a small spring m³ constrains it normally in an extreme position.

Upon the drum R may be secured a sheet T of a recording material such as paper. An electric-circuit W containing a source of current w connects in series the binding post g⁸ on the contact strip G, the collar H, the poles P of the synchronizer and the electro-magnet M. This circuit, passing as it does, through the contact strip G and the rotating arm e' will evidently be broken whenever said arm e' is out of contact with the strip G and vice-versa, hence an impulsive current is propagated in the circuit w; this current includes in series the coils p of the poles P, as shown. Furthermore as the height of this arm is affected directly by the action of the transparent representation B of the subject, upon the selenium cell N, it follows that the duration of these impulses is directly controlled. The effect of changes of the duration of these impulses upon the recording magnet M and the recording point m' causes an image of the subject to be reproduced upon the recording sheet T. This action results from the picture or image impulses which actuate the armature of the magnet M in a vibrating manner at a uniform rate, the impulses themselves being of variable duration within the limits of the rate of propagation.

The magnets M record variably, *i. e.* sometimes producing a wide and at other times a narrow record, similar to the effects produced under patent issued to applicant Feb. 45 16th, 1897, #577,373. In this patent the use of a selenium cell is shown in connection with a subject having its half tones broken up into parallel lines of varying widths forming alternate opaque and transparent parts which affect the selenium to a maximum and minimum degree alternately, at a uniform rate, though as stated the maximum or minimum effects may continue for variable periods. In the instance cited the pitch 50 of the lines or distance apart is uniform and the rotation being uniform the rate of propagation obviously is uniform also. It is also obvious that since the opaque and transparent portions vary in width, the duration 55 of the impulses will be variable.

Referring to the subject matter of this application, the image that is to be transmitted is not broken up into lines but it is a "transparency" or negative such as is well known 60 in the photographic art. It does not have

any ordinarily visible grain, reticulation or arbitrary black portions with transparent—"white"—interstices between them, such as is found in the usual half-tone reproductions of photographs. This subject is placed 70 upon the transparent cylinder as shown and a source of illumination is provided which is carried through a small opening n⁸ and directed upon a selenium cell N which may be of any of the well known forms obtainable on the market, and it is immaterial, whether the source of illumination be within 75 the drum as shown or without, and the selenium cell within, as one form is the equivalent of the other.

The manner of recording the impulses is immaterial, as an instance, a medium such as a sheet of celluloid may be used which has been coated with any suitable removable opaque material which will be scraped off intermittently as the drum rotates in front of the recording magnets, or a sensitive photograph film and suitable well known shutter arrangements operated by the magnets M may be used, or the specific method shown 80 in the patent referred to can be utilized equally well.

The arrangement of the gear-train O is such that if the drum R were rotated at substantially the same rate as the transmitting drum A the armature or needle o' would pass between two successive poles P during the same intervals of time that successive impulses pass in the circuit W. Now should there be any tendency for the drum R to lag 95 behind the transmitting drum the poles will become energized or excited before the armature o' reaches two of them and these two poles will exercise an attraction upon the armature and accelerate it; this acceleration 100 will be communicated through the gear-train O back to the drum R and it also will be accelerated. In like manner the drum R is retarded when necessary. Within the drum A may be a source of illumination a² 110 behind which may be provided a reflector a which is adapted to concentrate the light directly upon the selenium cell N.

The spindle E may be rotated at a high rate of speed and should it be desired to 115 drive the spindle E at an even multiple of the velocity of the drum A, I accomplish this by furnishing the belt, pulleys a' and c with small spurs or projections a³ and c' which engage with openings in the belt, as will be understood. It will be manifest from the above that the impulses in the circuit W serve not only to record an image of the subject, but also afford means for synchronizing 120 the transmitting and receiving apparatus.

It should be understood that I do not limit myself to the specific means shown as other means can be employed without departing from the spirit of my invention.

It is of course obvious that as the image 130

may not extend all the way around the drum there may be a blank space which, through the break in continuity of the strip G, between g' and g^2 , will continue to transmit 5 periodic impulses at the same rate as those of the image proper, though of uniform duration, as nothing would be found on this portion of the drum to cause them to be variable.

10 The feature of being able to continue the impulses throughout the entire circumference of the drum is very important as there will be no opportunity for the devices to lose step on account of discontinuity of the 15 impulses.

It may be said that the synchronizing impulses are continuously applied while the machines are in rotation and at intervals during each revolution "image impulses" are, 20 so to speak, superposed upon the synchronizing impulses by causing these impulses of normally uniform duration to vary their time factor, with respect to their individual characteristics, within the limits of their rate 25 of propagation.

The recording magnets will record during each entire revolution of the drums and when not indicating combined synchronizing and image impulses they will record the 30 synchronizing ones alone if the inductive and mechanical time constant of the recording magnets makes them responsive to the shortest recurring break in the circuit, which is however sufficient to effect the synchronizer magnets and thereby prevent the formation of errors that can become accumulative.

What I claim is:—

1. The method of reproducing photographs, or representations thereof, which 40 consists in causing an electric current of normal intensity to conform to the varying image tonality of a pictorial subject and thereby transmit said image, in simultaneously by means of said current controlling the movement of the receiving and transmitting apparatus in a synchronous manner and in suitably recording said image.

2. The method of reproducing photographs, or representations thereof, which 50 consists in causing the varying tonal or image characteristics of a pictorial subject to change the conditions of an electric current in conformity therewith without materially affecting its intensity, in utilizing the 55 said electric current to synchronize the transmitting and recording apparatus and in suitably recording the received image.

3. The method of reproducing photographs or representations thereof, which 60 consists in using the same electric current to simultaneously transmit an image of a pictorial subject, and synchronizing the transmitting and recording apparatus without materially changing the intensity of the

current and in suitably recording the transmitted image.

4. The method of reproducing photographs, or representations thereof, which 70 consists in propagating electric impulses, in transmitting an image of a pictorial subject by means of said impulses, in synchronizing the apparatus by the said impulses without materially modifying the intensity of current and in suitably recording said 75 image impulses.

5. The method of reproducing photographs, or representations thereof, which 80 consists in propagating electric impulses of normal strength at a uniform rate, in transmitting a pictorial image by means of said impulses, in simultaneously synchronizing the apparatus, and in suitably recording the transmitted image.

6. The method of reproducing photographs, or representations thereof, which 85 consists in propagating electric impulses at a uniform rate, in varying the duration of said impulses by means of a pictorial subject, in synchronizing the apparatus by 90 means of said impulses and in suitably recording the same.

7. The method of reproducing photographs, or representations thereof, which 95 consists in impressing an electric current by means of separate agencies, such as a pictorial image and a continuous synchronous control acting independently of the image, the two agencies being coincident in effect as to rate and periodicity but differential as 100 to modifications produced by the image, in simultaneously transmitting the image and synchronously controlling its reproduction and in suitably recording the transmitted image.

8. The method of reproducing photographs, or representations thereof, which 105 consists in continuously propagating electric impulses, in controlling the duration of said impulses by means of a pictorial subject, in 110 transmitting an image by means of said impulses, in synchronizing the apparatus by means of the same impulses and in suitably recording such impulses.

9. The method of reproducing photographs, or representations thereof, which 115 consists in continuously propagating electric impulses at a uniform rate and periodically varying duration, in utilizing the varying duration of said impulses to affect the recording of an image and in utilizing the uniformity of rate of said impulses to maintain equal progress of the transmitting and recording apparatus.

10. The method of reproducing photographs, or representations thereof, which 125 consists in continuously propagating electric impulses at a uniform rate, in periodically varying the duration of the impulses, by means of a pictorial subject, in affecting 130

- a recording instrument by means of the duration of said impulses, in simultaneously affecting synchronizing apparatus by means of the uniformity of rate of said propagations and in suitably recording the same.
11. The method of reproducing photographs, or representations thereof, which consists in continuously propagating impulses in a circuit extraneous of that included by a pictorial subject, in modifying said impulses by means of said subject, in transmitting an image by means of said modified impulses, in also maintaining synchronous movement of the transmitting and recording apparatus by means of all of the impulses and in suitably recording the transmitted impulses.
12. The method of reproducing photographs, or representations thereof, which consists in continuously propagating electric impulses at a uniform rate in a circuit extraneous of a pictorial subject, in varying the duration of said impulses by means of the subject, in recording an image of said subject by means of said impulses and in synchronizing the transmitting and receiving apparatus by the same impulses.
13. The method of reproducing photographs, or representations thereof, which consists in progressively moving a recording material with respect to an electrically controlled recording device, in propagating electric impulses of varying duration, in causing all of said electric impulses to successively and simultaneously actuate the recording device and a suitable synchronizer.
14. The method of reproducing photographs, or representations thereof, which consists in synchronously controlling the rate of movement of a recording surface, in directing the synchronism by means of an electric current of normal strength, in simultaneously causing the said electric current to produce a record, conformable to a pictorial subject without materially affecting its strength.
15. The method of reproducing photographs, or representations thereof, which consists in differentially moving a recording surface, in positively moving a means of control, in actuating said means of control and producing a record by means of electric

impulses propagated at a uniform rate of varying duration conformably with a pictorial subject.

55

16. The method of reproducing sketches, photographs, or representations thereof, which consists in propagating electric impulses independently of the subject and varying the duration of said impulses by means of variations in light and shade of the subject, and suitably recording the same.

17. The method or reproducing sketches, photographs, or representations thereof, which consists in propagating electric impulses of fundamental intensity extraneously of the subject and selectively varying the said impulses without affecting their intensity by means of variations of light and shade of the subject, and suitably recording the same.

65

18. The method of reproducing sketches, photographs, or representations thereof, which consists in propagating electric impulses normally of equal duration, and selectively varying the duration of said impulses by means of the light and shade of the subject, and suitably recording the same.

75

19. The method of reproducing sketches, photographs, or representations thereof, which consists in propagating electric impulses at a uniform rate, and selectively varying the duration of said impulses by means of the variations of light and shade of the subject, and suitably recording the same.

80

20. The method of reproducing sketches, photographs, or representations thereof, which consists in causing a device sensitive to light and shade to be actuated by a juxtaposed subject thereby propagating an electric current, in producing successive displacements between the subject and said device while continuously maintaining a definite distance between them, and in suitably recording the variations of the electric current.

90

In testimony whereof I affix my signature in presence of two witnesses.
